SPRAY HEAD

Stanley Isenberg, Chicago, Ill.

Application January 2, 1947, Serial No. 719,865

2 Claims. (Cl. 299—145)

1

This invention relates to spray heads of the type commonly used in the home, in barber shops and in beauty parlors for head or hair washing.

Spray heads of this type are conventionally constructed of rubber and include a generally dome-shaped hollow body portion having a central water inlet at the top for attachment to a rubber hose. A perforated spray plate closes the wide opening at the bottom. A flaring skirt depends peripherally from the body portion all around the spray plate. Such a spray head may be grasped manually, when operated, and moved over or along the head to spray water thereon. The edge of the skirt prevents splashing and confines the water spray to the area encompassed by the skirt.

Reference is made to my copending application Serial No. 667,607, filed May 16, 1946, for a disclosure of a spray head devoid of a depending skirt but provided with adjusting means for selectively changing the delivery of water from a substantially columnar stream to a fine spray, and vice versa. The adjusting means of said head include a manually operated lever arm projecting radially past the lower rim of the spray head.

It is one of the objects of the present invention to provide a spray head including adjusting means of the type indicated together with a depending skirt slotted to permit operation of the lever arm of the adjusting means whereby the spray head can be adjusted to deliver either a columnar stream of water or a spray, and the spray can be confined to the area encompassed by the skirt.

Other and further objects and features of this invention will become apparent from the following detailed description of a preferred example shown in the drawing, and from the appended claims.

In the drawing:

Figure 1 is a side elevational view of a spray head according to the present invention;

Figure 2 is a transverse cross sectional view taken along the line 2—2 of Figure 1; and

Figure 3 is an enlarged vertical cross sectional view taken along the line 3—3 of Figure 1.

A rubber spray head 10 includes a hollow generally dome-shaped main body portion 11 terminating in a central neck 12 pierced by an inlet opening 13 and has a metal nipple 14 sealed and frictionally retained therein and projecting therefrom. Over the projecting nipple portion a water hose 15 is fitted and held in place by anularly and constrictingly applied metal rings 16. The lower margin of the body portion 11 is

formed with an annular external reinforcing peripherally extending rib 17 and an annular internal groove 18 which extends through 360° and receives the margin of a metallic spray plate 19 described in greater detail hereinbelow. The spray head 10 is further provided with a depending outwardly flared peripheral skirt 20 pierced by a horizontal slot 21 extending generally parallel to the rib 17 slightly below the spray plate 19.

The spray plate 19 is provided with a large central aperture 25 and a number of small apertures 26 between the central aperture 25 and the outer margin of the spray plate. The internal margin of the spray plate 25 is suitably curved upwardly to align the edge thereof horizontally for cooperation with a sheet metal circular disc 27 provided with a number of perforations 28. The disc 27 is seated on upturned edges of the spray plate around the aperture 25. The disc has a flat arm 29 extending therefrom pivoted to the upper side of the disc 27 by a short rivet 30 rigidly connected to the arm 29 and passing through a small oversized hole in the disc 27. The rivet 30 has an integral curved operating arm 31 extending first downwardly from the disc 27 and then radially thereof out through the slot 21 in the skirt 20. Swinging of the arm or handle 31 in a counter-clockwise direction (see Figure 2) will cause the disc 27 to uncover the central spray plate aperture 25. The amount of returning movement of the disc 27 is limited by a short arcuate stop member 32 extending from the arm 29 so as to strike against the inside of the main body portion 11 when the disc 27 covers the aperture 25. Uncovering movement is limited by the striking of the disc 27 against the inside of the main body portion 11. Thus, the arm 31 can perform only a limited pivotal movement about the rivet 30. The slot 21 is made sufficiently long to accommodate this limited movement.

The body portion 11 is provided with an integral inverted frusto-conical water guiding portion 35 terminating in an annular flat portion 35' of uniform thickness defining an opening 36 spaced from, aligned with and smaller than the aperture 25. Spaced radial ribs 37 of triangular cross section integral with the body 11 and the portion 35 support the proximal portion 35.

A circular metal screen 40 is positioned in the lenticular chamber defined by the body portion 11 and the portion 35 between the inlet 13 and the opening 36.

The body portion 11 and the skirt 20 are molded in one piece. This piece is sufficiently resilient

3

and the screen 40 is sufficiently flexible to permit insertion of the screen 40 into the interior of said piece. The resiliency of said piece also permits the insertion of the spray plate 19 into the groove 18.

In use, the spray head 10 is grasped by the operator and held within the palm, the skirt being deformed by digital pressure as required to permit escape of water between the edge of the skirt 20 and the layer of hair against which the spray head is applied.

The alignment of the orifice 36 with the aperture 25 and the smaller size of the former avoids any interference by the inner edge of the spray plate 19 (around the aperture 25) when a column of water issues from the orifice 36. Thus, when columnar flow of water is effected by displacement of the disc 27 from the aperture 25, such columnar flow originates from the aperture 25. The inner margin of the guiding cone 35 being spaced from the inner margin of the spray plate 19, the whole perforated upper area of the spray plate 19 is made accessible to water flowing from the orifice 36 when the aperture 25 is overlaid by the perforated disc 27.

The lenticular form and angular periphery of the chamber defined in the spray head between the inlet 13 and orifice 36 make possible the insertion and retention of the screen 40 which serves not only to catch solid particles but also to reduce the turbulence of the stream of water flowing through the spray head.

In compliance with the requirements of the patent statutes I have here shown and described a preferred embodiment of my invention. It is, however, to be understood that the invention is not limited to the precise construction here shown, the same being merely illustrative of the principles of the invention. What I consider new and desire to secure by Letters Patent is:

1. A spray head comprising a generally dome-shaped hollow body having a water inlet and having an outlet, a perforated spray plate disposed in said outlet, said perforated spray plate having a central aperture, a perforated disc overlying a portion of the spray plate, said body having a flexible skirt around said outlet, said skirt having a slot opening therethrough extending in general parallelism with the edge of said outlet adjacent the spray plate on the side thereof remote from the water inlet, and an elongate lever member pivoted on said spray plate and having a first arm extending inside the chamber formed by the dome-shaped body and said spray plate and terminating in said perforated disc, said lever member including a second arm extending below said

4
spray plate and through said slot opening, for manually moving said disc into and out of registration with said spray plate aperture for selective adjustment of said spray head for delivery of water passing therethrough either as a columnar stream or as a spray.

2. A spray head comprising a generally dome-shaped hollow body having an upper water inlet and a lower water outlet adapted to receive the hereinbefore mentioned perforated spray plate, said body being formed with an internal inverted frusto-conical portion originating angularly from the inside of said body and defining a central orifice above said outlet, a screen seated in said hollow body with its edge inserted into the angle formed by said frusto-conical portion with said inside of the main body, a perforated spray plate seated in said outlet and having an aperture aligned with but spaced from and larger than said orifice, said body having a flexible peripheral skirt around said outlet and pierced by an arcuate slot therethrough adjacent the spray plate on the side thereof remote from the water inlet, and an elongate lever member pivoted to said spray plate and having a first arm extending over said spray plate and terminating in a perforated disc, said lever member including a second arm extending below said spray plate through said arcuate slot and movable from one edge of the slot to the other edge thereof in an arcuate movement centered about the pivot of the lever member to the spray plate, for manually turning the lever to move said disc into and out of registration with said spray plate aperture whereby said spray head may be selectively adjusted for delivery of water passing therethrough either as a columnar stream or as a spray.

STANLEY ISENBERG.
